UNITED STATES PATENT OFFICE.

JOHN BECKER, OF MARENGO, IOWA.

DESIGN FOR A PLOW-CLEANER.

45,408.

Specification for Design.

Patented Mar. 17, 1914.

Application filed January 15, 1914. Serial No. 812,347. Term of patent 14 years.

To all whom it may concern:

Be it known that I, JOHN BECKER, a citizen of the United States, residing at Marengo, in the county of Iowa and State of Iowa, have invented a new, original, and ornamental Design for a Plow-Cleaner, of which the following is a specification, reference being had to the accompanying drawing, forming part thereof.

The drawing is a perspective view of a plow cleaner showing my new design.

I claim:

The ornamental design for a plow cleaner, as shown.

JOHN BECKER.

Witnesses:

CHAS. I. DENZLER,
C. G. MCKEE.
